UNITED STATES PATENT OFFICE.

JOHN LAWSON, OF CENTRAL FALLS, RHODE ISLAND.

AUTOMATIC CIRCULAR-KNITTING MACHINE.

1,140,269.

Specification of Letters Patent. Patented May 18, 1915.

Application filed June 17, 1911. Serial No. 633,720.

To all whom it may concern:

Be it known that I, JOHN LAWSON, a citizen of the United States, residing at Central Falls, in the county of Providence and State of Rhode Island, have invented certain new and useful Improvements in Automatic Circular-Knitting Machines, of which the following is a specification.

My invention relates to automatic knitting-machines, but more particularly to knitting-machines for automatically producing seamless stockings, so-called; that is, stockings in which the leg and foot portions are tubular and without a sewed seam.

The object of the present invention is to provide a circular seamless machine adapted for the knitting of stockings or other tubular fabrics, and by means of which invention the stocking or fabric may be provided with longitudinal lines of tuck-strokes which extend for only a portion of the length of the stocking or tubular fabric.

For the production of lines of tuck-strokes tuck-needles, that is, needles having longer latches than the regular needles, are employed, there being one tuck needle for each line of tuck-strokes, and for the accomplishment of the object above set forth these tuck-needles should be caused at one time or in one portion of the stocking to knit tuck-strokes and at another time or in another portion of the stocking to knit plain or ordinary stitches.

The invention consists in a circular knitting machine having in combination with the knitting cylinder and the usual needles and knitting-cams, one or more tuck-needles, and means for automatically operating the latter at predetermined times as to whether said tuck-needle or needles shall knit tuck-strokes or shall knit plain stitches.

The invention further consists in an automatic circular knitting machine having in combination with the usual needles and devices for producing plain knitting, one or more tuck-needles, a movable tuck-cam for operating said tuck-needle or needles, a main rotary device provided with cam surfaces for moving said tuck-cam alternately into and out of operative position, and a second rotary device for independently controlling the position of said tuck-cam.

The invention also consists in certain combinations and arrangements of parts to be hereinafter set forth and claimed.

It may be stated that the present inven-

tion, represented in the accompanying drawings, is well adapted to be associated or attached to and coöperate with the automatic circular stocking-knitting machine 60 illustrated in J. D. Hemphill's U. S. Patent No. 933,443, certain parts of which machine are reproduced in the present drawings. In said patented knitting-machine the needle-carrying or knitting-cylinder is revolute. 65 A main cam-shaft having a drum, &c., fixed thereon is arranged to make only one revolution during the production of the stocking; the machine is further provided with a relatively large continuously revolute spur-gear, so proportioned, connected and timed 70 with relation to other movable members of the machine that it makes one turn to four of the needle-cylinder; both the said cam-shaft and gear rotating in one direction. 75 In the adaptation of my present invention to said patented knitting-machine, the cam-shaft and gear referred to are utilized, in connection with additional new parts, or devices, for automatically producing longitudinal lines of tuck-strokes in the tubular portions of the stocking.

In the accompanying three sheets of drawings, Figure 1 represents, in partial section and elevation the general relation of the improved parts to the knitting-cylinder, cam-shaft, &c., as in the act of producing tuck-work, the tuck-cam (not shown) for the instant being in the depressed position; Fig. 2 is a corresponding top plan view, in reduced scale, viewed from the horizontal plane or line 2-2 of Fig. 1; Fig. 3 is a vertical sectional view, taken substantially on line 3-3 of Fig. 1; Fig. 4 is a partial top plan view, showing the relation of the tuck-cam to the knitting-cylinder, stitch-cam, &c.; Fig. 5 is a sectional view, similar to Fig. 3, but showing the gear advanced 90° in its rotary movement, and having its cam-rib in temporary engagement with the roll of the tuck-cam lever, thereby correspondingly elevating the tuck-cam; Fig. 6 is a front elevation, in partial section and enlarged scale, showing more in detail the vertically guided tuck-cam or supplemental raise-and-draw cam in the depressed position; Fig. 7 is a similar view, showing the cam in the elevated position; Fig. 8 is a top plan view corresponding with Fig. 6, showing in addition portions of the needle-cylinder and needles; Fig. 9 is a partial transverse section, in enlarged scale, taken

through the cylinder, &c., corresponding substantially with line 9—9 of Fig. 13; Fig. 10 is a vertical sectional view, in partial elevation and enlarged scale, taken substantially on line 10—10 of Fig. 4, showing the tuck-cam depressed, corresponding with Figs. 1 and 3; Fig. 11 represents, in enlarged scale, an elevation of the parts, viewed from the line x—x of Fig. 4; Fig. 12 represents the same when the cam-block is moved outward from the cylinder; Fig. 13 is an elevation representing a development of the several stitch-cams, guards and tuck-cam, viewed from the inner side or face of the cylinder; Fig. 14 is a back side elevation of the tuck-cam and its housing, the cam being in the fully depressed position; Fig. 15 is a transverse section, taken on line 15—15 of Fig. 13, and also showing both short-but and long-but needles passing the tuck-cam; Fig. 16 represents the position of the upper or hook portion of the long and short-but needles corresponding with the indication of similarly numbered needles designated in Fig. 13 and showing the short-latch needles as in producing regular or plain circular knitting; Fig. 16½ indicates the position of the corresponding long-latch or tuck-needle when acted upon by the elevated tuck-cam in said regular work; Fig. 17 represents various positions of the long-latch needle in producing, say the first circular course in the tuck-stitching operation, the tuck-cam then being depressed; Fig. 18 represents corresponding positions of the long-latch needle in producing the second circular course, the tuck-cam then being elevated and having a pair of loops on the needle; Fig. 19 represents the next circular course of the tuck-needle, and is practically a repetition of the positions shown in Fig. 17, except that the double loops have been cast off into the web; and Fig. 20 represents in an exaggerated manner and greatly enlarged scale, a front view of the arrangement of the threads to form in the web a longitudinal line or wale of tuck-stitches presenting the appearance of split-foot work.

50 As hereinbefore stated, certain parts of the said patented knitting-machine are shown in the present drawings; that is to say, N designates the revolute needle-carrying or knitting-cylinder; C the latch-ring; G the sinker-cap ring, capable of short vibratory movements in a horizontal plane; n⁶ the sinker-head-ring, secured to the cylinder; f, f¹ the vertical right and left ends of the main frame or housing; t the table; s¹ the main cam-shaft, adapted to make only one complete revolution during the knitting of a stocking; i¹ a spur-gear adapted for continuous rotation in one direction through the medium of a smaller gear i mounted on the driving-shaft s (Fig. 1); g a horizontal

plate in which the cylinder revolves and to which the cam-ring r is secured, the plate and the members secured to it being capable of short vertical movements, and g¹ indicates portions of a bevel-gear secured to the lower end of the cylinder N—see Fig. 9. To the rear or left end of the said cam-shaft s¹ is secured a disk c having suitable cam-lugs, c¹, c², c³, disposed around and fixed to its rim; these lugs, in coöperation with other parts or elements about to be described, impart vertical movement to the supplemental draw-cam, or tuck-cam A, for actuating the tuck or long-latch needles. A tilting lever d, pivoted at f² to the frame f¹ (Figs. 1 and 2) has its front end d¹ in engagement with the cam-disk c, its rear end being jointed to a vertical rod d³; the upper end of the latter is slotted, see d⁴, and jointed to a short lever e¹ fixed to a suitably mounted, comparatively long, horizontal rock-shaft e, disposed below and near the table t. To the opposite end of shaft e is secured an arm or tuck cam lever e², the latter having a truck-roll e³ mounted in its free end, said lever when depressed positioning the roll in the circular path of and arranged to be engaged by suitable cam-lugs, i², i², fixed to said gear i², all as clearly shown. These cam members, as drawn, are oppositely arranged and separated circumferentially by a space or gap, the length of the circular arc being, say 90° each. A lever-arm e⁴ is also fixed to shaft e, or it may be integral with lever e¹; a spring s² connecting its free end with the lower lever d—see Fig. 1. As thus devised and arranged, the latter lever, when in engagement with the plain portion of the disk's rim, operates to keep the roll e³ positioned in the path of the cams i², and so as to be intermittently engaged by them, thereby vibrating the shaft e twice during each revolution of the gear, the spring s² causing the shaft and its members to swing in the reverse direction back to the normal position again. Owing to the presence of the slotted joint d⁴ of the connection d³ such vibratory action of the shaft e, &c., is or may be continued while the members d and d³ remain stationary in the position represented in Fig. 1. Said movements of shaft e, in connection with other coöperating members, later described, automatically impart correspondingly intermittent vertical movement to the tuck-cam A. When the lever d is in engagement with any of the lugs of the cam-disk c, thereby moving the connecting-rod d³ downward, the result is to swing the roll e³ upward out of the path of the revolving cams i², thus at the same time moving the tuck-cam into its upward or operative position, to cast the loops from the tuck-needles' latches; the tuck-cam and also the several members d, d³, and rock-shaft, remaining stationary meanwhile until 130

the next change or movement of the disk c takes place.

The means represented for imparting direct vertical reciprocatory movements to the 5 tuck-cam from the said lever-arm e^4 consists of the rod h , jointed to the latter and extending upward through table t . To the upper end of this rod is secured a short horizontal member h^1 , to which, in turn, is 10 hinged an extension h^2 , having its inner or free end forked to freely receive between its upper and lower ears h^3 , h^4 , the outwardly projecting portion of pin p^1 ; the latter being fixed to the cam A and extending therefrom 15 through a vertically slotted opening r^7 formed in the box or casing B secured to the stationary cam-ring r , all as clearly shown in the drawings. As thus devised, it is clear that upon vertically reciprocating the rod h , 20 the cam A is correspondingly moved. To the underside of arm h^2 is jointed a link h^6 , in turn pivotally connected to the slideable block D (Fig. 4) carrying the stitch-cams. Upon moving the block outward from the 25 normal knitting position, as for example, when transferring or "topping" is being done, the member h^2 will thereby be correspondingly swung in a lateral direction, thus temporarily withdrawing it away from the 30 tuck-cam's pin to permit the knitting cylinder to be freely rotated. In order that the pin will automatically resume its normal position between the said ears concurrently with the act of returning the cam-block to 35 its inward or working position, an edge of the lower ear h^4 is extended laterally to form an inclined guide h^5 leading to the opening between the two ears and adapted to engage the underside of the pin and 40 facilitate its entrance into said opening. Fig. 11 represents the normal working relation and position of the several parts, and Fig. 12 the same when the cam-block is retracted from its cylinder. The arrangement 45 above described is adapted to both the elevated and depressed positions of the tuck-cam, since the link h^6 is pivoted to the cam-block.

Now, assuming the machine to be normally running, the step-by-step movements 50 of the cam-shaft s^1 to which the cam-disk c is secured are or may be effected by a controlled pattern-chain and coöperating mechanisms in a well-known way. In the 55 arrangement of the said concentric peripheral sections or raised lugs of cam c , represented in Fig. 1 of the drawings, the relation and timing are such that when the free end d^1 of lever d rests, say upon lug c^1 , as 60 in producing a stocking having its leg portion consisting of continuous plain or regular courses of knitting, the movable members connected with the lever and tuck-cam elevate the latter to its operative position 65 (see Fig. 13), whereby the long-latch tuck-

needles are at the same time caused to operate and cast their loops from the latches; the loops of all the other needles of the set are also cast from the respective latches during each normal circular course. When the 70 lever d thus rests upon any of the lugs the roll e^3 is thereby swung upward or outwardly so as not to be engaged by the cams i^2 of the revolving gear i^1 .

In order to produce tuck-stitch work at 75 any predetermined point in the knitting of the leg part, say at the point where the high-splice is to be commenced, the axial movement of shaft s^1 then carries the lug c^1 past the lever, the spring s^2 instantly dropping 80 it onto the bottom of the peripheral gap v , thereby moving the tuck-cam downward to its tucking position (corresponding with the temporary retention of the loops on the tuck-needles) and positioning the roll e^3 in 85 the path of the cams i^2 so as to be intermittently engaged and actuated by them. While the lever d remains in the depressed position the tuck-cam is adapted to be moved up and down twice during each rotation of 90 the gear i^1 , corresponding with four circular courses, thereby simultaneously casting off a pair of loops from the tuck-needle in every other or alternate course. At the termination of the leg part or commencement 95 of the heel the lug c^2 is advanced under the lever, thereby for the time being moving the roll e^3 and tuck-cam upward and permitting the tuck-needle or needles to work as usual in connection with the other needles 100 while the cylinder is reciprocating and the heel is being formed. At the completion of the heel and commencement of the foot part and resumption of circular knitting, and also in order to produce tuck-stitching there- 105 in, the further rotation of the shaft s^1 carries lug c^2 past the lever, the latter then drops into the gap or plain portion v^1 , thereby again automatically placing the roll e^3 110 in position to be acted upon by the cams i^2 , substantially as before described with respect to tuck-stitching the leg. At the completion of the foot or commencement of the toe pocket the cam-lug c^3 will have been angularly advanced under the lever d , thereby 115 elevating and maintaining the tuck-cam in its raised position while the toe portion is being made, the cylinder meanwhile reciprocating. At the completion of the toe the lever drops into the gap v^2 , followed by 120 knitting a few circular looper courses and running off the work, the machine then stopping. While thus stopped the usual transferring or "topping" operation is effected, that is, in case half-hose are being 125 produced. The act of retracting the cam-block B from the cylinder also withdraws the arm h^2 from the pin p^1 , thereby, in co-operation with the dropping of the usual cam-plate g , permitting all the needles to be 130

temporarily pressed downward to or below the tops of the sinkers, and so that upon applying the top-carrying transfer-ring to the cylinder, its points will properly register with the needle-grooves. Fig. 11 represents the pin-supporting arm h^2 in the normal working relation, and Fig. 12 the same in the said retracted position. In case the machine is to be adapted to automatically produce ladies' stockings or string-work, the said gap or space v^2 is filled with a lug or section c^4 (indicated by the dotted line in Fig. 1), or the several sections may be integral or connected together to form a curved single long section. In such case the stocking or work is run off the machine and the thread next fed to the then empty needles automatically to commence the knitting of the new stocking, the machine being in continuous action. The knitting of the stocking, and including the production of tuck-stitch work in the leg and foot portions, are effected in substantially the same manner and by the means before described with respect to the production of tuck-strokes in half-hose. By changing or varying the length and position of a cam-section, as c^1 , circumferentially upon the member c , rows of tuck-strokes may be produced in the stocking leg, as desired.

In Fig. 13 (which represents a diagrammatic development of the cams and the inner circumference of the knitting-cylinder) the dotted lines and arrows α indicate the row of butts and direction of needle-movement in producing circular knitting. The numerals 1 to 8, inclusive, indicate various positions of the same needle during the knitting of a circular course. The upper dotted wave-line H indicates the corresponding movements of the top end of the hooks, the dotted horizontal line N^1 indicates the top of the stitch-ring k or rather the upper edge o of the sinkers, represented more clearly in Fig. 9. The cam-ring r (referring to Fig. 13) has an opening in which is located the pair of main stitch or draw-cams r^1 , r^2 , (usually secured to a sliding block D , Fig. 4) and the coöperating upper and lower central guard members r^3 , r^4 ; p , p , designate the two narrowing pickers, and A and B the auxiliary or supplemental guided, vertically movable draw-cam or tuck-cam and its easing, respectively; the latter adapted to be secured to the ring r by screws p^2 . In a knitting-machine embodying my improvement and as adapted to produce tuck-stitch work only one set of needles is used, the same comprising two series, *i. e.*, short-butt and long-butt needles a and b , respectively. All the latches of both series of needles are uniform in length, and may be termed short-latches, except only that the two end needles b^1 of the semi-circular row of long-butt needles have longer latches. In the descrip-

tion herewith the needles are designated as short-latch and long-latch needles.

In the diagram, Figs. 13 and 16, the numerals 1, 2, 3, 4, 5, 6, 7, and 8 indicate various positions of the two series of short-latch short and long-butt needles a and b in producing a course of plain or regular circular knitting during a complete revolution of the needle-cylinder. The thread u (Fig. 16) is fed into the successive hooks between positions 3 and 4, the previously formed loop on each needle operating to close the latch, as usual, while the needle, position 4, is moving downward by means of stitch-cam r^2 , so that when it is at the lowest point, 5, its old loop is cast off over the closed hook into the web, and leaving the new loop on the needle; the needle then in moving upward through the new loop u^1 opens the latch and remains thereon until it reengages the companion stitch-cam r^1 , thereby moving the needle upward to cast the loop from its latch. The height of the last-named stitch-cam is somewhat less than the other cam, but ample, however, to cast off the loops from the latches of all the short-latch needles. In producing plain or regular courses of stitches, in which two of the long-butt needles, b^1 , have longer latches, the tuck-cam A is in the elevated position—see Figs. 5, 13, and 15, the lever d then being in engagement with the corresponding lug of cam member c . The long butts of the needles b and b^1 enter the open passage α^5 , and upon engaging the elevated tuck-cam the needles are deflected upward to cast their respective loops u^1 from the latches, the cam and its guide r^6 instantly moving these needles downward to the normal level. In Fig. 16 $\frac{1}{2}$, 7 and 8 indicate the corresponding positions of the long-latch needles at said casting-off point; each of these latter needles in the production of the next course (Fig. 17) receives new thread in its hook, the latch closes and its old loop is cast off and interlooped into the stitches of the web, substantially as before stated. When the tucking-cam A is thus elevated the roll e^3 is correspondingly elevated above the path of the continuously rotating arch-shaped cams i^2 . In knitting circular courses having both plain and tuck-strokes in which loops are not cast from the tuck needles during the course, the corresponding relation of cam c , lever d , etc., to the revolving gear i is substantially as indicated in Fig. 1. The cams i^2 successively and intermittently engage the roll e^3 and correspondingly actuate the cam A up and down; the spring s^2 automatically retracting the tuck-cam when the roll e^3 drops from the respective cams i^2 . When thus dropped the cam A causes the new loop to be retained on the latch of the tuck-needle so that in producing the next circular course, Fig. 18, the latch will remain open

and so that at the lowest position, 5, the hook will hold the old loop u^1 and the newer loop u^2 , formed from the last introduced thread u . Immediately thereafter, the gear i^1 in its rotation advances cam i^2 into engagement with the roll e^3 , thereby correspondingly oscillating the rock-shaft to elevate or reposition the tuck-cam, and so that said needle is thereby moved up and down, the action being to simultaneously cast both the said loops, u^1 , u^2 , from its latch onto the needle body—see positions 7 and 8, Fig. 18. The double-loop carrying long-latch needle b^1 in the knitting of the next circular course remains open—see positions 1, 2, and 3, Fig. 19, until the new thread is fed into its hook; at which instant the action of stitch-cam r^2 , &c., causes the latch to close, both loops, u^1 , u^2 , then bearing against the front of the latch—see corresponding position 4, Fig. 19. In passing the base or lower end of cam r^2 the loops u^1 , u^2 , are simultaneously cast off the needles into the web—see position 5—and the new thread converted into a loop u^1 bearing against the face of the open latch when the needle is in the normal position, 6. The tuck-cam A is next depressed, thereby causing the latch of needle b^1 to remain open until the thread is again fed into its hook, as in Figs. 17-18; the operations just described being repeated in an intermittent manner during the production of tuck-stitching. That is to say, oppositely disposed tuck loops are interlooped into normal courses of circular stitches.

By providing the knitting-machine with applicant's improvement, the single set of needles, comprising both long and short-butt needles, mounted as usual in all the needle-grooves of the knitting-cylinder, is adapted to produce plain, seamless stockings and also stockings having certain of the circular courses formed of plain or regular stitches, and other circular courses of the same web consisting of both regular and tuck-strokes.

In Fig. 20, which represents a front view of a portion of a knitted web, $w-w$ indicate the longitudinal rows or wales of regular stitches and w^1 a longitudinal row of tuck-strokes substituted for the corresponding or omitted regular row, and interlooped into the adjacent rows $w-w$. The loops proper, u^1 , are located at the back of the web, the inclined or converging portions, u^3 , of the stitches being in front. The semi-loop u^2 , or portion of the thread associated with each of the stitches of the said row w^1 , extends transversely across between the contiguous rows w and is interconnected with the latter and with the elongated portion of the tuck-stitch.

It will be seen that with the construction and combination of parts above described the tuck-needles employed will be caused to

knit tuck-strokes at one portion of the stocking or other tubular fabric, and at another portion of the stocking or fabric the same tuck-needles will be caused to knit plain or ordinary stitches, this being due to the fact that means are provided whereby the manner of operating the tuck-needles may be varied. It will be further understood that in the case of a stocking, for example, the lines of tuck-strokes may, by properly varying or timing the operation of the controlling devices, be located in any portion of the stocking which may be desired. Thus, if desired, the lines of tuck-strokes may be located at the back of the leg portion, and for the reason that by the means shown and described the tuck-needles which operate to produce lines of tuck-strokes on the back of the leg portion may be caused, when the heel is reached, to knit plain or ordinary stitches, and to continue the knitting of such plain stitches through the heel, sole, and toe portions of the stocking. It will also be understood that while the invention is particularly useful in connection with the knitting of seamless stockings, said invention may also be employed in connection with the knitting of any other tubular fabric in which it may be desired to have lines of tuck-strokes in a certain portion or portions thereof, but not in other portions.

I claim as my invention and desire to secure by U. S. Letters Patent:—

1. In an automatic circular knitting-machine having a revolubly mounted knitting cylinder provided with uniformly spaced grooves in which only latch needles are mounted, the latches of one or more of said needles exceeding in length the respective latches of the other needles, the combination with means coöperating with all the needles for converting a thread into a plain circular course of knitting, of a tucking-cam, revoluble cam mechanism operatively connected with the tucking-cam so as to temporarily prevent the latter from moving upward to cast loops from the latches of the tuck needles in tuck-knitting, a block member provided with stitch-cams, and means connected with said tucking-cam and block member for moving the latter radially in and out with relation to the knitting cylinder, said last mentioned means being arranged to position a member of the tucking-cam whereby it is adapted to operatively engage the block member when the latter is moved inward.

2. In an automatic circular knitting-machine having a revoluble needle cylinder provided circumferentially with uniformly spaced all-latch-needles, one or more of them being tuck-needles, the combination therewith of a vertically slidable tucking-cam, an actuated main cam-shaft, means controlled

from said cam-shaft for positioning the tucking-cam upward in the path of the tuck-needles whereby the engagement of the latter with the tucking-cam operates to cast the 5 loops from the latches of the last named needles to produce, in coöperation with the other needles, a course of plain, circular knitting, a spring for retracting the tucking-cam back to its normal position, continuously revoluble 10 cams and instrumentalities connected therewith and with the tucking-cam for reciprocating the latter to produce tuck-strokes at predetermined intervals in alternate courses of circular knitting, and means for moving 15 the knitting-cams into and out of action.

3. In an automatic circular knitting-machine having a revoluble needle cylinder provided circumferentially with uniformly spaced all-latch-needles, one or more of them 20 being tuck-needles, the combination therewith of a vertically slidable tucking-cam, main rotary cam mechanism for positioning the tucking-cam for engagement with said tuck-needles, continuously revoluble 25 independent cam mechanism rotating at less speed than the revoluble needle-cylinder, and means operatively connecting said main and independent rotary cam mechanisms, said last named means having a member 30 thereof provided with a slotted joint and connecting lever, whereby the said main cam acts to place the tucking-cam upward to produce normal knitting at one point in the production of the tubular web and acts to 35 place the tucking-cam in position so as to be acted upon by said independent rotary-cam mechanism to produce tuck stitch knitting at predetermined other points in the web, substantially as herein set forth.

4. In an automatic circular knitting-machine, the combination with the knitting-cylinder having long-butt and short-butt needles movably mounted therein, and devices, including stitch-cams, secured to a 45 slideable cam-block, adapted to coöperate with the needles for producing circular knitting, of an independent supplemental or tuck cam arranged to be engaged by the long-butt needles, means for automatically actuating the last-named cam at predetermined 50 points in knitting continuous circular courses, and means coöperating with said cam-block for automatically rendering the supplemental cam inactive concurrently with the act of retracting the cam-block from the 55 cylinder.

5. In a circular knitting-machine provided with a needle-carrying cylinder, and stitch-cams movable in and out with respect to the face of the cylinder, the combination therewith of a supplemental or tuck cam disposed in the path of, and when in use, adapted to be engaged by certain of the needles, means for automatically moving the 60 said supplemental cam into the operative and inoperative positions, and means for rendering the supplemental cam temporarily inoperative concurrently with the act of moving the stitch-cams outward from the 65 cylinder. 70

In testimony whereof I have affixed my signature in presence of two witnesses.

JOHN LAWSON.
